(57) **CLAIM**

The ornamental design for a combined hair brush and comb, as shown and described.

DESCRIPTION

FIG. 1 is a front view of a combined hair brush and comb, showing my new design;

FIG. 2 is a back side view of the combined hair brush and comb;

FIG. 3 is a left side view of the combined hair brush and comb, shown enlarged for ease of illustration;

FIG. 4 is a right view of the combined hair brush and comb, shown enlarged for ease of illustration;

FIG. 5 is a top plan view of the combined hair brush and comb;

FIG. 6 is a bottom plan view of the combined hair brush and comb;

FIG. 7 is a perspective view of the combined hair brush and comb;

FIG. 8 is another perspective view of the combined hair brush and comb, shown in an exploded configuration.

FIG. 9 is a front view of the comb, shown isolated from the hair brush portion of the design, shown enlarged for ease of illustration;

FIG. 10 is a back side view of the comb, shown isolated from the brush portion of the design, shown enlarged for ease of illustration;

FIG. 11 is a left side view of the comb, shown isolated from the brush portion of the design, shown enlarged for ease of illustration;

FIG. 12 is a right view of the comb, shown isolated from the brush portion of the design, shown enlarged for ease of illustration;

FIG. 13 is a top plan view of the comb, shown isolated from the brush portion of the design, shown enlarged for ease of illustration;

FIG. 14 is a bottom plan view of the comb, shown isolated from the brush portion of the design, shown enlarged for ease of illustration; and,

FIG. 15 is a perspective view of the comb, shown isolated from the brush portion of the design, shown enlarged for ease of illustration.

The broken line in FIG. 8 represents an unclaimed portion of the brush handle.

1 Claim, 15 Drawing Sheets
